UNITED STATES PATENT OFFICE.

WILLIAM F. YOUNG, OF SPARTANBURG, SOUTH CAROLINA.

SAFETY-ENVELOP.

932,742.

Specification of Letters Patent. Patented Aug. 31, 1909.

Application filed March 30, 1909. Serial No. 436,821.

To all whom it may concern:

Be it known that I, WILLIAM F. YOUNG, a citizen of the United States, residing at Spartanburg, in the county of Spartanburg and State of South Carolina, have invented certain new and useful Improvements in Safety-Envelops; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to the class of envelops, but more particularly to a safety envelop which is designed especially to be used for the sealing of money packages, valuable express parcels, papers and the like, in such manner that it will be practically impossible to surreptitiously open the envelop and rifle the contents thereof without tearing and disfiguring the envelop.

My invention consists in the novel construction, arrangement and provision for sealing the envelop in such manner that the only seal occurs at one end of the same and in such manner that three separate and distinct seals are provided at one end of the envelop.

Referring to the accompanying drawings: Figure 1 is a plan view of the envelop blank. Fig. 2 is a plan view illustrating the envelop partly folded. Fig. 3 is a perspective view illustrating the envelop in position to receive its contents. Fig. 4 is a perspective view illustrating the envelop after it has received its contents and is first sealed.

Like numerals of reference indicate the same parts throughout the several figures in which;

1 indicates the envelop which is provided with two wings 2 and 3, the sealing flap 4, front 5 and sealing flap 6, said sealing flap 6 being in effect a double flap and comprising the gummed portion 7 and the gummed portion 8.

Referring to Fig. 2 it will be seen that the entire backs of the wings 2 and 3 are suitably gummed at 9 while the end flap 4 is gummed at 10.

Having thus described the construction of the envelop the same is folded and employed as follows: The blank having been cut as shown in Fig. 1 and the portions gummed as illustrated in Fig. 2 the wings 2 and 3 are

folded over upon the body 11 of the envelop as shown in Fig. 2. The front portion 5 is then folded down upon the wings 2 and 3, and by reason of the gum on said wings the said back is caused to firmly adhere to the wings, it being clearly shown in Fig. 2 that the wings 2 and 3 are of such dimensions as to meet each other along the line 12. When the envelop is folded in this position it assumes the appearance as illustrated in Fig. 3 and the same is ready to receive its contents, it being of course understood that the envelop is placed upon the market in this form. When it is desired to seal the envelop after it has received its contents the end flap 4 is folded over the mouth 13 of the envelop and the gummed face 10 of said envelop is moistened which causes said flap to firmly adhere to the surface 14 of the envelop, thus effectually closing the mouth 13 and holding the contents within the envelop. After the end flap 4 has been sealed as just described the gummed portion 7 of the sealing flap 6 is moistened and said flap 7 is caused to firmly adhere to the outer surface 15 of the end flap 4, thus causing a double seal to be effected at that point. When this seal has been accomplished the sealing flap 6 is bent over the mouth of the envelop and the gummed portion 8 caused to firmly adhere to the back of the envelop.

It will thus be seen that there is only one portion or part of the entire envelop at which the contents can be inserted or removed from the envelop and that is at the sealed end thereof. It will also be seen that when the end flap 4 is effectually sealed, the portion 7 of the flap 6 effectually sealed over the end flap 4 and the portion 8 of the end flap 6 carried over and effectually sealed upon the back of the envelop that a sealing is effected at the only point at which the envelop can receive or deliver its contents, it of course being understood that the envelop can be torn or cut at the opposite end or along the sides thereof for the purpose of conveniently removing the contents.

Having thus fully described my invention what I claim as new and desire to secure by Letters Patent of the United States is;

1. An envelop comprising a body portion 11, two wings 2 and 3 on said body portion and folded over upon the same, said wings meeting together, a front portion 5 folded back upon the wings 2 and 3 and securely fastened thereto, an end flap 4 adapted to

be turned over the mouth of the envelop and securely fastened to the wings 2 and 3, a sealing flap 6 comprising sealing portions 7 and 8, the portion 7 being adapted to be 5 securely fastened or sealed to the outer surface of the end flap 4, the portion 8 of the sealing flap 6 being adapted to be passed over the end flap 4 and to be securely sealed or fastened to the back of the envelop, sub- 10 stantially as described.

2. An envelop comprising a body, wings thereon adapted to be folded over said body, a front portion adapted to be folded down upon said wings and sealed thereto, an end 15 flap adapted to be folded over the mouth of the envelop and to be securely sealed to the said wings, a sealing flap comprising two portions, one portion of which is adapted to be securely sealed to the outer surface of the

said end flap, the other portion to be adapted 20 to be folded over the said end flap and to be securely sealed to the back of the envelop.

3. An envelop comprising a body, an end flap adapted to be folded over the mouth of the envelop and securely sealed, a sealing 25 flap comprising two portions, one of said portions being adapted to be securely sealed to the outer surface of said end flap and the other of said portions being adapted to be folded over the said end flap and securely 30 sealed to the back of the envelop.

In testimony whereof, I affix my signature, in presence of two witnesses.

WM. F. YOUNG.
